UNITED STATES PATENT OFFICE.

FRED CARON, OF DETROIT, MICHIGAN.

AUTOMATIC WEATHER STRIP.

Application filed May 5, 1922. Serial No. 558,671.

To all whom it may concern:

Be it known that I, FRED CARON, a citizen of the United States, residing at Detroit, in the county of Wayne and State of Michigan, ⁵ have invented new and useful Improvements in Automatic Weather Strips, of which the following is a specification.

The object of my said invention is the provision of an automatic weather strip for ¹⁰ use on doors, characterized by simplicity and strength in construction and reliability in operation.

To the attainment of the foregoing, the invention consists in the improvement as hereinafter described and definitely claimed.

In the accompanying drawing, forming part of this specification:—

Figures 1 and 2 are views showing my improvement as properly arranged relative to ²⁰ a door, Figure 1 showing the working parts in normal or idle positions, and Figure 2 showing the parts in the positions they assume when the door is closed.

Figure 3 is a vertical section taken ²⁵ through the weather strip in the line 3—3 of Figure 2.

Figures 4 and 5 are detail views herein-after explicitly referred to.

Similar numerals of reference designate ³⁰ corresponding parts in all of the views of the drawings.

My novel weather strip is carried in the manner illustrated by the lower end portion of the door 1, and among other elements the ³⁵ weather strip comprises a metallic body plate 2. The weather strip also comprises an auxiliary plate 4 spaced from the body plate 2 and having a flange 3 fixed with respect thereto.

Carried by the metallic body plate 2 and interposed between the said plate 2 and the auxiliary plate 4, Figure 3, are the working parts of the weather strip, the said working mechanism including a thrust bar 6, a pad ⁴⁰ 7 carried thereby, levers 8, and a retractile spring 9. The thrust bar 6 is formed of a single piece of sheet metal bent transversely, and the pad 7 is arranged and secured by pins 5 or other means between the side portions of the said bar 6. In the upper edge or ⁴⁵ bight portion of the bar 6 are provided openings 10, Figures 3 and 4, and through these openings 10 extend anchors 11 on bodies 11^x which carry apertured bracket plates 12. ⁵⁰ The levers 8 are provided with eyes 13 and are also provided with lateral studs 14 by

which they are pivotally connected to the bracket plates 12 as illustrated. Said levers 8 are fulcrumed at 15 to the body plate 2, and the spring 9 is interposed between and ⁶⁰ connected to the eye 13 of one lever 8 and the stud 14 connecting the other lever 8 to the respective plate 12; it being understood in this connection that the studs 14 are headed as shown in Figures 1 to 4 so that ⁶⁵ the spring 9 may be reversed when the door is hinged at the right hand side instead of at the left hand side or edge as appears in Figure 2. The retractile spring 9 is arranged in parallelism to the body plate 2, and serves ⁷⁰ to yieldingly retain the bar 6 in and to return said bar 6 to the position shown in Figure 1. When, however, the door is closed and the bar 6 is thrust toward the right, the spring 9 will be put under tension. From ⁷⁵ this it will be readily understood that while when the door is closed the bar 6 is thrust endwise toward the right, and the pad 7 is crowded against the floor or against the door sill; yet when the door is opened, the spring ⁸⁰ 9 will operate to promptly raise the bar 6 and the pad 7 so as to prevent the latter from interfering in any measure with the free opening of the door.

It will be manifest from the foregoing ⁸⁵ that my novel strip is simple and inexpensive in construction, is susceptible of ready application to a door, and is adapted when properly applied to a door to reliably operate and to withstand for an indefinite period ⁹⁰ of time the rough usage to which weather strips of doors are ordinarily subjected.

For the sake of prolonging its usefulness and assuring proper operation the thrust bar 6 is provided at its forward end and ⁹⁵ adjacent to its upper edge with a bumper portion 15', preferably of metal and designed to sustain the wear when the bar 6 is engaged for the rearward movement thereof.

I have entered into a detailed description ¹⁰⁰ of the construction and relative arrangement of the parts embraced in the present and preferred embodiment of my invention in order to impart a full, clear and exact understanding of the said embodiment. I do not ¹⁰⁵ desire, however, to be understood as confining myself to the said specific construction and relative arrangement of parts inasmuch as in the future practice of the invention various changes and modifications may be ¹¹⁰ made such as fall within the scope of my invention as defined in my appended claims.

Having described my invention, what I claim and desire to secure by Letters-Patent, is:—

1. The combination in a weather strip, of a body, levers connected at intermediate points in their lengths with said body and having upper and lower arms, a padded thrust bar pivotally connected to and carried by the lower arms of the levers, and a retractile spring interposed between and connected to the upper arm of one lever and the lower arm of the other lever.
2. The combination in a weather strip, of a body, levers carried by said body and hav-

ing upper and lower arms, a thrust bar of 15 inverted U-shape in cross-section having openings in its top, a pad carried by said thrust bar, brackets secured on the thrust bar by anchors extending through said openings, pins extending through and connecting the lower arms of the levers and the brackets, said pins having heads, and a retractile spring connected to the upper end of one lever and connected at its opposite end to the headed pin or stud pivotally connecting the 25 lower arm of the other lever to a bracket.

In testimony whereof I affix my signature.

FRED CARON.
